CHRISTIAN ANDREASON, OF SACRAMENTO, CALIFORNIA.

SPARK-PLUG.

1,356,954.

Specification of Letters Patent. Patented Oct. 26, 1920.

Application filed February 19, 1919. Serial No. 278,029.

To all whom it may concern:

Be it known that I, CHRISTIAN ANDREASON, a citizen of the United States, residing at Sacramento, in the county of Sacramento and State of California, have invented new and useful Improvements in Spark-Plugs, of which the following is a specification.

This invention relates to a spark plug for internal combustion engines.

It is the principal object of this invention to provide a spark plug which will afford adequate sparking surface for insuring that the gases within an internal combustion engine may be properly ignited and at the same time will supply simple means by which the electrodes may be cleaned of carbon without removing the plug from its position within the cylinder head of the engine.

The present invention is particularly concerned with a spark plug having a fixed metallic casing carrying a ring-shaped electrode adapted to coöperate with a central electrode member to produce a spark, this central member being revolvably mounted upon a stem extending upwardly through the center of the spark plug and scraping the surface of the ring-shaped electrode during its revolution.

The invention is illustrated by way of example in the accompanying drawings, in which—

Figure 1 is a view of the spark plug as seen in longitudinal vertical section.

Fig. 2 is an end view of the spark plug disclosing the relation of the electrodes to each other.

In the drawings, 10 indicates the metallic plug portion which is formed with a tubular threaded extension 11 adapted to be positioned within the threaded bore of an engine cylinder head. As a matter of convenience the body portion of this plug is hexagonal in shape to facilitate the tightening or removal of the plug. An internally threaded tubular extension 12 is formed at the upper end of the plug and is adapted to receive a lock-nut 13. This nut circumscribes an insulated tube 14 which extends downwardly through the central bore of the plug and being formed of dielectric material desirably supports a central electrode sleeve 15. The insulator 14 is formed with an annular ring

intermediate its length, which ring seats within the tubular bore 12 and is engaged by the lock-nut 13 which clamps it against its seat. The ring portion of the insulator, as indicated by the numeral 16, is V-shaped in section and is supplied with packing washers 17, adapted to securely seal the central opening of the plug and prevent the exhaust of gases around the insulator. The central electrode sleeve 15 is formed of metal and provides a guiding support for the central electrode stem 18. The sleeve is exteriorly threaded near its upper end and receives a wing-nut 19. A lock-nut 20 holds the sleeve in any desirable position, with relation to the electrode.

An opening is formed through the center of the wing-nut 19 and the stem 18 extends therethrough. Mounted upon the upper end of this stem is a thumb-nut 21 by which the stem may be rotated. The upper end of the sleeve 15 is split and externally tapered and coöperates with the nut 19 to adjustably hold the stem. It will thus be seen that when the nut 19 is tightened, the stem will be rigidly held. The lower end of the electrode stem 18 is formed with a pair of arms 24. These arms extend radially from the longitudinal axis of the stem and stand in proper spaced relation to a circular electrode 25. This electrode is fixed beneath the tubular portion 11 of the plug 10 and secured thereto. Thus, by the application of a current to the stem 18 and to the plug 10, a spark may be created between the electrode arms 24 and the electrode 25. The collar 23 may be adjustable, if desired, and thus regulate the spark gap existing between the two electrodes.

As shown in Fig. 1, the arms 24 are downwardly and outwardly tapered, thus producing a knife edge and a flat underface adapted to pass along the upper face of the electrode 25. Thus, when the nut 19 is loosened, the electrode arms 24 may be lowered until they bear forcibly upon the circular electrode, after which the stem 18 may be revolved by manipulation of the thumb-nut 21 and the carbon deposited upon the electrode thus removed. It will also be noted that this will produce a scouring action between the flat face of the electrode arms 24 and the upper flat face of the electrode 25,

thus cleaning the two surfaces and insuring that the proper spark will be obtained. After this operation has been completed, the stem may be drawn outwardly, as desired, 5 after which the nut 19 may be tightened and the various electrode members thus held in a rigid relation to each other.

If will thus be seen that the spark plug here disclosed is not only simple in its construction and the manner in which it is assembled but will also provide a dual spark gap and means whereby the contact points may be properly cleaned without removing the plug from its operative position.

15 While I have shown the preferred form of my invention, it will be understood that various changes in the combination, construction and arrangement of parts may be made by those skilled in the art, without departing from the spirit of the invention as 20 claimed.

Having thus described my invention, what

I claim and desire to secure by Letters Patent is—

A spark plug comprising a metallic body 25 member, a circular electrode mounted upon the lower end thereof, a tubular insulator detachably fixed within said body member, a metallic sleeve carried by said tubular member, an electrode stem extending through 30 said sleeve, means for fixing said stem in relation thereto, means for locking the stem in relation to the insulating member, electrode arms formed at the lower end of said stem and means whereby said stem and arms may 35 be revolved to remove carbon deposits from the first named electrode.

In testimony whereof I have hereunto set my hand in the presence of two subscribing witnesses.

CHRISTIAN ANDREASON.
